COMPENSABLE JOINT

John E. Carter, Geneseo, Ill.

Application January 21, 1935, Serial No. 2,681

4 Claims. (CL. 94—18)

The invention relates particularly, although not exclusively, to joints of the inner vertical edges of adjacent concrete slabs of concrete highways, streets, and the like.

- 5 It is well known that the co-efficient of expansion of concrete highways, streets, sidewalks, and the like, is relatively great which results in considerable damage being effected to said concrete unless efficient means are provided to permit the 10 concrete to expand and contract without exerting strain on relatively great lengths of said concrete. For this reason, concrete highways, streets and sidewalks usually comprise a plurality of concrete slabs whose inner edges are spaced apart 15 a sufficient distance to permit the slabs to expand fully without contacting the inner edges thereof. Either permitting the inner edges of the concrete slabs to contact each other, or filling the spaces between said slabs with any substance 20 incapable of being readily compressed results in the concrete buckling and cracking when the temperature becomes sufficiently high to cause the concrete to expand beyond the limit of the co-efficient of flexibility of said concrete.
- 25 Heretofore, considerable difficulty and inconvenience has been experienced by builders of concrete highways, streets, sidewalks, and the like, in providing joints of concrete slabs which will compensate for the expansion and contraction of said slabs and prevent damage to said slabs during said expansion and contraction. Frequently the spaces between the adjacent slabs are filled with plastic fillers such as asphalt, or like substance, and after a period of time has 30 elapsed, dirt, water, and other foreign substances, as a result of natural elements and movement of vehicles over the highway, enter the spaces between the slabs and adjacent the filler especially after the filler has been compressed by expansion 35 of the slabs, and the slabs contract when the temperature is lowered, or after the filler has cracked or otherwise disintegrated. In other instances the spaces between the slabs are filled with metal fillers which are adapted to be 40 loosened, and permit entrance of dirt, water and other foreign substances, between the slabs after the fillers have been damaged or have been rendered inefficient as a result of the expansion and contraction of the slabs.
- 45 It is well known that when the spaces between the slabs of a concrete highway, street or sidewalk are filled with sand, dirt, and the like, such materials cannot be compressed, when the concrete slabs expand, whereby expansion of the 50 slabs causes the slabs to warp or bend, crack,

and otherwise be damaged because concrete is inflexible and unless the slabs are free to expand without any or a great deal of resistance the slabs will crack.

5 Therefore, the objects of the invention are to provide a simple, efficient and practical joint of the inner edges of the concrete slabs forming a concrete highway, street, sidewalk, or the like; to provide a resilient member in the space between said slabs, said resilient member being adapted 10 to be compressed when said slabs expand and being adapted to expand when said slabs contract whereby the space between said slabs is at all times sealed against entrance of dirt, sand, water, or other foreign substances; to provide 15 means to retain said resilient member substantially in a fixed and predetermined position with respect to said slabs, said means being disconnected from said slabs whereby movement of said slabs, caused by expansion and contraction, is 20 unlikely to impart movement to said means or effect damage to said slabs; and to provide a foot fixed to the bed of said highway, a pair of spaced apart forms or retainers adapted to be 25 connected with the inner edges of said slabs, said forms or retainers being connected with said foot in a manner adapted to permit said forms or retainers to slide horizontally when horizontal movement is imparted to said inner edges of 30 said slabs by expansion and contraction, whereby the inner edges of said slabs are adapted to move horizontally without substantial interference or restriction by the joint or any portion thereof.

35 The invention consists in the combination of the elements, arrangement of the parts and in the details of the construction, as hereinafter claimed.

In the drawings:

Fig. 1 is a plan view of a ribbon, or roadway, 40 partly broken away;

Fig. 2 is a section taken on a line corresponding to 2—2 in Fig. 1, with parts broken away;

Fig. 3 is a section taken on a line corresponding to 3—3 in Fig. 2, with the concrete removed, and 45 with parts broken away;

Fig. 4 is a section taken on a line corresponding to 4—4 in Fig. 2, with the concrete removed, and with parts broken away;

Fig. 5 is a section taken on a line corresponding to 5—5 in Fig. 2, with the concrete removed, and 50 with parts broken away;

Fig. 6 is a section taken on a line corresponding to 6—6 in Fig. 3 and with parts broken away; 55

Fig. 7 is a side elevational view of a block, with parts broken away;

Fig. 8 is a perspective view of a sleeve;

Fig. 9 is a section taken on a line corresponding to 9—9 in Fig. 2, with the concrete removed, and showing parts broken away; and

Fig. 10 is a perspective view of a form retainer, with parts broken away.

In the preferred construction of the invention, comprising the compensable joint 1, I provide the vertical spaced apart angular form retainers 2 and 3 each of which comprises the upper and lower horizontal legs 4 and 5 having their inner ends integrally formed with the vertical body 6. In the upper legs 4 are a plurality of spaced apart slots 7 having received therethrough the vertical stay-rods 8 whose lower ends 9 are embedded in the road bed 10, which may be formed from suitable material, such as asphalt, sand, gravel, concrete, or the like. The road bed 10 is supported by the ground over which the intended ribbon or highway 11, sidewalk, or the like, is constructed.

The ribbon 11 is formed from a plurality of horizontal slabs 12 having their upper surfaces 13 in horizontal alignment and having their adjacent inner vertical edges 14 and 15 spaced apart, thereby forming the spaces or cuts 12' therebetween which extend transversely of the ribbon 11 and in parallel relation with each other.

The upper legs 4, of the form retainers 2 and 3, are embedded in the inner vertical edges 14 and 15 of the adjacent slabs 12 and spaced from the upper surfaces 13 of the slabs. The upper legs 4 are embedded in the slabs 12 so that the vertical bodies 6 are fixed to the outer surface of the inner edges 14 and 15 of the slabs.

The lower horizontal legs 5, of the form retainers 2 and 3, are supported by the horizontal body 16, of the angular foot or support 17. Integrally formed with the outer edges 18 and 19, of the support 17, are the downwardly extending legs 20 and 21 which are embedded in the road bed 10.

In the lower horizontal legs 5, of the form retainers 2 and 3, are the slots 22, whose walls extend outwardly from the bodies 6. Slidably received in the slots 22 are the rivets 23 whose heads 24 slidably contact the upper surfaces of the legs 5. Each of the rivets 23 have the stem 25 received in the hole 26 in the body 16, of the support 17. The rivet 23 has the shoulder 27 received in contact with the upper surface of the body 16 of the support 17, and the enlarged lower end 28 of the rivet 23 is received in contact with the lower surface of the body 16 of the support 17, whereby the rivet is retained in fixed position with respect to the support 17 of either or both of the form retainers 2 and 3. The legs 5 are adapted to slide horizontally in contact with the upper surface of the body 16 of the support 17 when movement, longitudinally of the ribbon 11, is imparted to the form retainers.

Positioned over the slots 22 and rivets 23 are the covers 29 having their inner and outer ends 30 and 31 fixed, as by the rivets 32, to the body 6 and legs 5 of the form retainers 2 and 3, whereby the slots 22 are kept free from concrete, dirt, and other foreign substances which may interfere with free horizontal slidable movement of the lower legs 5, of the form retainers.

During construction of the ribbon 11, and after the stay-rods 8 are fixed in the road bed 10 and green concrete is poured onto the road bed and 75 in contact with the form retainers 2 and 3, which

forms the slabs 12, the green concrete is prevented by the covers 29 from entering the slots 22 or contacting the rivets 23.

Received in the spaces or cuts 12', and between the inner vertical edges 14 and 15, of the slabs 12, and in contact with and between the vertical bodies 6 of the form retainers 2 and 3, are the resilient strips or blocks 33 which may be formed from rubber or other suitable material. The upper edge 34, of each of the blocks 33, is substantially in horizontal alignment with the upper surfaces 13 of the slabs 12. The lower edge 35, of the block 33, is in contact with the upper surface of the body 16, of the support 17, and supported by the supports. 15

Fixed to the inner surfaces of the bodies 6, of the form retainers 2 and 3, are the nipples 36 and 37 having the internal threads 38 therein to which are threaded the external threads 39 on the outer surfaces of the inner ends of the sleeves 40 and 41 which extend horizontally. Slidably received in the sleeves 40 and 41 and extending through the holes 42 and 43 in the bodies 6, of the form retainers 2 and 3, is the floating or slidable bar 44 which is received through the hole 45 in the resilient block 33, whereby the block 33 is retained in predetermined position with respect to the slabs 12.

When the slabs 12 expand, as a result of variations of the temperature of said ribbon 11, the inner edges 14 and 15 of the slabs 12 advance toward each other, and when the slabs contract the edges 14 and 15 retreat from each other.

As previously mentioned, the bar 44 is free to move horizontally within the sleeves 40 and 41, inward and outward movement of the edges 14 and 15, of the slabs 12, caused by expansion and contraction of the slabs, does not effect movement of the bar 44 which retains its predetermined position for the purpose of maintaining the resilient block 33 in stationary and predetermined position with respect to the inner edges 14 and 15, of the slabs 12, and the form retainers 2 and 3. When the slabs 12 expand, as their temperature increases, and the inner edges 45 thereof advance toward each other, the resilient block 33 is compressed. When the slabs 12 contract, as a result of their temperature decreasing, and the inner edges thereof retreat from each other, the resilient block expands and remains in close and sealing contact with the bodies 6, of the form retainers 2 and 3, and also in sealing contact with the inner edges of the slabs above the horizontal legs 4 of the form retainers 2 and 3. 55

When constructing the ribbon 11, the vertical legs 20 and 21, of the supports 17, are embedded in the road bed 10 after which the form retainers 2 and 3 are properly positioned in spaced apart relation with each other, depending upon the temperature at the time of installation. The supports 17 and the retainers 2 and 3 have been previously assembled with the rivets 23 connecting the legs 5, of the form retainers 2 and 3, with the body 16 of the supports 17, and the covers 29 65 are fixed to the form retainers 2 and 3. Then the form retainers 2 and 3 are fixed in an adjusted position as by inserting the vertical stay-rods 8 through the slots 7 in the horizontal legs 4 and the lower ends of the stay-rods are driven 70 into the road bed 10. Then the resilient blocks 33 are inserted between the bodies 6 of the form retainers 2 and 3, preferably under slight compression. Then the bar 44 is inserted through the nipples 36 and 37, respectively, fixed to the 75

bodies 6, of the form retainers 2 and 3, and through the holes 45 in the resilient blocks 33 and positioned so that the distance which the ends 46 and 47 of the bar 44 extend outwardly from the bodies 6, of the retainers 2 and 3, is approximately the same. Then the sleeves 40 and 41 are screwed into the nipples 36 and 37. Then the slabs 12 are formed by pouring suitable material, such as concrete, into the forms previously constructed to form the outer edges of the ribbon 11 until the upper surface of the slabs is in horizontal alignment with the upper edge of the adjacent resilient blocks 33. While the concrete sets or hardens the retainers 2 and 3 automatically become fixed to the edges 14 and 15, of the slabs 12, and the upper edges of the slabs contact the upper end of the block 33.

An advantage of the invention is that the resilient block 33 is adapted to seal the space 12' between the slabs 12, whereby entrance of sand, dust, water, or other foreign substances, in said space is prevented. Also, the resilient block 33 is retained in a predetermined and substantially fixed position with respect to the retainers 2 and 3, and the edges 14 and 15 of the slabs 12 as by the bar 44, which is disconnected from the slabs whereby the slabs are adapted to move horizontally by expansion and contraction without damaging the joint 1 of the slabs 12.

Another advantage of the invention is that the retainers 2 and 3 are slidably connected with the foot or supports 17, whereby the retainers 2 and 3 are adapted to slide horizontally and yet be supported by the supports 17 when the edges 14 and 15 of the slabs move horizontally inwardly and outwardly as a result of expansion and contraction of the slabs, and the connections of the supports 17 with the slabs 12 remains substantially the same and without damage to the slabs irrespective of ordinary movements of the slabs.

Still another advantage of the invention is that the upper edge of the block 33 is formed from resilient material, such as rubber, and is unlikely to impart excessive vibration to a vehicle which travels over the highway 11 because the resilient block 33 is adapted to be compressed in horizontal alignment with the upper surfaces of the slabs 12 by contact of the vehicle wheels. Moreover, when the resilient block 33 is utilized in the joint 1 between the slabs of a sidewalk the foot of a person, who walks over the sidewalk, will compress the contacted upper edge of the block substantially in horizontal alignment with the upper surfaces of the slabs 12.

While I believe that the form of the invention illustrated in the drawings and referred to in the above description, as the preferred embodiment, is efficient and practicable, yet realizing that the conditions concurrent with the adoption of the device will necessarily vary, I desire to emphasize the fact that changes in the details may be resorted to, when required, without sacrificing any of the advantages of the invention as defined in the claims.

Various changes may be made in the general form and arrangement of mechanical parts described without departing from the invention. Hence I do not limit myself to the precise details

of the materials or the size and shape thereof as set forth, but consider myself at liberty to make such changes and alterations as fairly fall within the spirit and scope of the appended and final claims.

What I claim as new and desire to secure by Letters Patent is:

1. The combination with an expansible and contractible concrete street positioned on a road bed and comprising a plurality of horizontal slabs 10 having spaced apart vertical inner edges and having their upper surfaces substantially in horizontal alignment, a vertical form retainer being fixed to each of said edges and having a space therebetween, a resilient block positioned between said 15 retainers, and sealing said space, means movably mounted in the edges of said slabs and extending through said block to retain said block substantially in predetermined position irrespective of movements of said slabs caused by expansion and 20 contraction, a foot member fixed in said road bed, means slidably connecting the lower edges of said retainers with said foot member, said last mentioned means adapted to prevent vertical movements of said retainers and permit horizon- 25 tal movements thereof.

2. The combination with an expansible and contractible concrete street positioned on a road bed and comprising a plurality of horizontal slabs having spaced apart inner edges, a form retainer 30 being fixed to each of said edges and having a space therebetween, a block positioned between said retainers, means movably mounted in the edges of said slabs and extending through said block to retain said block substantially in pre- 35 determined position, a foot member fixed in said road bed, means slidably connecting the lower edges of said retainers with said foot member, said last mentioned means adapted to prevent vertical movements of said retainers and permit 40 horizontal movements thereof.

3. The combination with an expansible and contractible street comprising a plurality of horizontal slabs having spaced apart vertical inner edges and having their upper surfaces substantially in horizontal alignment, a vertical form retainer being fixed to each of said edges and having a space therebetween, a resilient block positioned between said retainers, and sealing said space, means movably mounted in the edges 45 of said slabs and extending through said block to retain said block substantially in predetermined position irrespective of movements of said slabs caused by expansion and contraction.

4. The combination with adjacent vertical 55 edges of horizontal concrete slabs having their upper surfaces substantially in horizontal alignment, of vertical retainers being spaced apart from each other and being fixed to said edges, means intermediate said retainers, and means to 60 retain said means in predetermined position with respect to said retainers, the upper edges of said retainers being lower than the upper surfaces of said slabs and the upper edge of said block being substantially in horizontal alignment with 65 the upper surfaces of said slabs.

JOHN E. CARTER.
